DESIGN FOR A KNITTED FABRIC

Joseph A. Viret, Teaneck, N. J.

Application March 17, 1941, Serial No. 99,643

Term of patent 3½ years

To all whom it may concern:

Be it known that I, Joseph A. Viret, a citizen of the United States, residing at Teaneck, in the county of Bergen and State of New Jersey, have invented a new, original, and ornamental Design for Knitted Fabrics, of which the following is a specification, reference being had to the accompanying drawing, forming part thereof.

The figure is a plan view of the knitted fabric, showing my new design.

I claim:

The ornamental design for a knitted fabric, as shown.

JOSEPH A. VIRET.
